RAILWAY COUPLER

Harry H. Wolfe, Columbus, Ohio, assignor to The Buckeye Steel Castings Company, Columbus, Ohio

Application December 21, 1953, Serial No. 399,298

10 Claims. (Cl. 213—72)

The present invention relates to a coupler for railway vehicles and more specifically pertains to the stem of a railway coupler which is constructed to permit a rear end portion of the shank to turn about the longitudinal axis of the draw bar while the coupler head remains in a fixed upright position.

It has been found desirable in discharging the contents of a railway car to invert the body of the vehicle whereby the load escapes therefrom. Such a dumping operation is advantageously carried out with apparatus wherein the car body is rotated about a longitudinal axis in alignment with the draw bars through substantially one hundred eighty degrees to effectively discharge granular or like materials from the car body of the hopper type. In such unloading operations it is desirable to have the car being dumped remain coupled to an adjacent upright railway vehicle and it is an object of the present invention to provide a coupler for a car to be dumped which will permit a coupler to remain in mated engagement with an adjacent upright coupler.

Another object of the invention is to provide a railway coupler with a stem so constructed that a rear portion thereof may rotate with respect to the coupler head thereby permitting the coupler to remain in coupled relationship with another coupler while the rear portion of the stem turns with the car body as it is rotated through substantially one hundred eighty degrees.

A more detailed object of the invention is to provide a coupler head with one stem portion which extends into a rear stem member and to provide a journal between the overlapping parts of the stem so as to permit the rear member of the stem to rotate about the longitudinal axis of the composite stem while the coupler head remains in a generally upright position.

A still further object of the invention is to provide a pivoted connection between a rear stem member for a coupler and a front stem member including detent means to normally retain the front stem member in a fixed position with respect to the rear stem portion and thereby maintain the coupler head in a fixed position when it is not coupled to another railway vehicle.

Other objects and features of the invention will be apparent to those skilled in the art as the present disclosure proceeds and upon consideration of the accompanying drawings and the following detailed description wherein an embodiment of the invention is disclosed.

In the drawings:

Fig. 1 is a plan view of a coupler provided with a swivel stem exhibiting the invention.

Fig. 2 is an enlarged horizontal sectional view taken on the line 2—2 of Fig. 3.

Fig. 3 is a sectional view taken on the line 3—3 of Figs. 1 and 2.

Fig. 4 is a transverse sectional view taken on the line 4—4 of Fig. 3.

Fig. 5 is a horizontal sectional view of the rear member of the stem taken on the line 5—5 of Fig. 6.

2

Fig. 6 is a sectional view of the rear stem member taken on the line 6—6 of Fig. 5.

Fig. 7 is an end view of the rear stem member taken in the direction of the arrow 7 of Fig. 6.

5 Fig. 8 is a transverse section taken on the line 8—8 of Fig. 6.

Fig. 9 is a plan view of a member adapted to fit in the rear stem member.

10 Fig. 10 is a sectional view taken on the line 10—10 of Fig. 9.

Fig. 11 is a transverse sectional view taken on the line 11—11 of Fig. 10.

Fig. 12 is an end view of the retaining member.

The present invention is directed to the draw bar of 15 a coupler whereby the rear member of the coupler stem may rotate about a longitudinal axis of the draw bar so as to enable the rear member of the coupler shank to turn with the draft rigging. The invention is adaptable to all types of couplers and in the embodiment disclosed a type "F" coupler head is shown at 14 in Fig.

1. The coupler head 14 is of a conventional type except for changes in the lock lift mechanism and the rotor lever as described and claimed in my copending application Serial No. 393,193, filed November 19, 1953.

25 The purpose of forming the coupler stem of two-parts is to permit rotation of the rear part of the shank with reference to the coupler head to thereby permit the coupler head 14 to remain in mated or coupled engagement with the coupler of another upright railway vehicle.

30 While the car body is turned through as much as one hundred eighty degrees to discharge material from the car body. The apparatus on which the car is arranged for such an unloading operation is so designed that it rotates the car body about the axis of the coupler draw bars.

35 A composite coupler stem assembly exhibiting the invention is shown in the drawings wherein the rear stem member is represented generally at 15 while the forward stem portion is indicated at 16 which may be formed integral with the coupler head. The rear stem member 15 is provided with a spherical shaped butt end 17 for cooperation with a follower of the draft rigging in the usual manner. A vertically disposed opening 18 is provided adjacent the rear end of the stem member 15 for accommodating a pin for connecting the coupler shank to nose portions of a yoke (not shown) in a known manner. A concave spherical surface 19 forms the rear boundary of the opening 18 for accommodating a bearing block (not shown) in a known manner so that the rear stem member 15 of the coupler may swivel horizontally and vertically. Other conventional butt end structures and connections may be provided at the rear end of the stem assembly.

40 The rear stem member 15 is provided with an elongated cavity 20 therein for accommodating an extension 21 carried by the front stem member 16. The rear stem member 15 is spaced from the front stem member 16 as shown at 22 in Fig. 1. The extension 21 is cylindrical shaped throughout a major portion of its length and projects into the cavity 20. A bearing surface 23 is provided 45 within the rear stem member 15 so that the extreme rear end of the extension 21 is journalled for rotation on this bearing surface. Another cylindrical surface 24 is provided on the forward portion of the rear stem member 15 within the cavity 20 for cooperation with a cylindrical neck 25 of the extension. The rear stem member 15 is provided with lugs 27 and 28 which cooperate with an enlarged boss 31 carried by the extension 21.

50 The extension 21 forming a part of the front stem is introduced into the rear stem member 15 through an opening 32 provided in the lower portion of the rear stem member 15. The cylindrical surface at the rear

end of the extension 21 is thus seated on the bearing surface 23 and the cylindrical portion 25 is seated for rotation on the cylindrical surface 24.

A filler member 34 shown in Figs. 9 to 12 is then mounted in place to close the opening 32 and to hold the two-part stem structure in assembled relationship. The filler member is provided with a cylindrical surface 36 for complementing the cylindrical bearing surface 23. A similar short segment of a cylindrical surface 37 is carried by the forward portion of the filler member 34 and complements the cylindrical surface 24 at the forward portion of the rear stem member 15. A recess 38 is formed in the filler member 34 for accommodating a segmental portion of the boss 31. A shoulder 41 adjacent the bearing surface 37 on the filler member 34 serves as another part of the lug structure at the front of the rear stem member 15. The shoulder 41 in cooperation with the lugs 27 and 28 and the shoulder 42 on the boss 31 serve to transmit the pulling forces from the coupler stem member 16 to the rear stem member 15.

The filler member 34 is secured in place by welding and the weld metal is applied along the transverse area 46 and the longitudinal areas 47 in Figs. 3 and 4. In order to facilitate application of the weld metal the lower edges of the rear stem member 15 are bevelled at 48 and the filler member is similarly bevelled at 49. Longitudinally extending shoulders 51 formed on the rear stem member 15 cooperate with shoulders 52 on the filler member 34 to accurately position the filler member within the opening 32. The filler member 34 may be clamped and held in position while the welding operation is carried out. The rear stem member 15 with the filler member 34 in place may be regarded as rear stem means.

The front end of the rear stem member is provided with a spherical shaped recess 61 as shown in Fig. 7. A relatively large aperture 62 is formed in the rear portion of the front stem member 16 for accommodating a ball 63 and a spring 64. The recess 61 is so positioned that when the coupler head 14 is in its normal upright position with the knuckle pin in a vertical position the ball 63 will be urged into the recess 61 and thus releasably retain the rear stem member 15 in a fixed position with reference to the front stem member 16.

The extension 21 is of such length as to terminate immediately forward of the pin receiving opening 18 to make the bearing structure as long as possible and thus counteract any tendency of the coupler head 14 and the front stem member 16 to droop with respect to the rear stem member. The lugs 27 and 28 carried by the rear stem member 15 and the lug shoulder 41 carried by the filler member 34 in cooperation with the shoulder 42 on the boss 31 transmit the pulling forces from the coupler head 14 to the rear stem member 15. The cylindrical surface 23 formed in the rear stem member in cooperation with the segmental cylindrical surface 36 on the filler member 34 provide for relative rotation of the parts but at the same time restrains the coupler head 14 and the front stem member 16 from drooping. This desirable characteristic is further attained by having the extension 21 bear on the cylindrical segment 37 and at the same time bear on the upper portion of the cylindrical surface 23 when all the parts are assembled. Clearance is provided at the bearings to provide freedom for rotation. The shoulders 51 in cooperation with the shoulders 52 permit the filler member 34 to be clamped in position after the front stem member is mounted in position with the extension 21 within the rear stem member 15 and such clamping may be maintained when the filler member is welded along three sides to the rear stem member.

It will be apparent that the rear stem member 15 is rotatable about the axis of the extension 21. Thus when the rear stem member 15 is attached to a draft rigging in the usual manner and when the car body is undergoing a dumping operation the rear stem member 15 will rotate about the axis of the extension 21 leaving the front stem

member 16 and the coupler head in an upright position. Accordingly the coupler head 14 may remain in coupled relationship with the coupler of a railway vehicle adjacent the car being dumped. During such relative rotation of the rear stem member 15 with respect to the front stem member the ball 63 rides on the flat front surface 72 of the rear stem member 15. When the car body is returned to an upright position the ball 63 re-enters the recess 61. Thus when the coupler head 14 is uncoupled from an adjacent coupler it will remain in an upright position by the restraint provided by the ball 63 cooperating with the recess 61.

While the invention has been shown and described in connection with a particular type of coupler and having a particular shaped rear end it will be appreciated that the invention is directed to structure providing for rotation of the rear portion of a coupler stem with regard to a coupler head. Thus rear end structure of coupler stem may be varied without departing from the spirit and scope of the invention and changes may be made in the details of the structure which provides for swiveling of the stem members without departing from the spirit and scope of the invention.

What I claim and desire to secure by Letters Patent is:

1. In a coupler for a railway car, a coupler head, a front stem member on said coupler head including an extension projecting rearwardly therefrom, a shoulder on the front stem member defining the forward end of said extension, rear stem means encasing said extension, bearing surfaces on the extension and the rear stem means spaced longitudinally of the extension whereby the stem means may rotate about the axis of the extension, lugs carried by the rear stem means, a boss on said extension cooperating with said lugs for transmitting pulling forces from the front stem member to the stem means, an abutment surface on a forward portion of the stem means cooperating with said shoulder for transmitting buffing forces, said abutment surface having a recess therein, and a spring actuated ball carried by the front stem member for entering said recess releasably retaining the stem means in one rotated position relative to the front stem member.

2. In a railway coupler, a coupler head, a front stem member carried by the coupler head projecting rearwardly therefrom, an extension on said stem member in axial alignment with the longitudinal axis of the front stem member, a cylindrical surface adjacent the rear end of said extension, a shoulder on said stem member defining the forward end of said extension arranged in a plane at substantially right angles to the longitudinal axis of the stem member, an annular boss on said extension of larger diameter than said cylindrical surface and spaced rearwardly from said shoulder, a second cylindrical surface on the stem member between said boss and said shoulder, a rear stem member having a cavity therein open lengthwise along the bottom thereof accommodating said extension, a segmental cylindrical bearing surface within said rear stem member at the rear of said cavity fitting about the first cylindrical surface on said stem member, a filler member closing said cavity, a segmental cylindrical surface carried by the filler member complementing said bearing surface, lugs on said rear stem member fitting between a forward portion of said boss and said shoulder, a segmental cylindrical second bearing surface on said lugs fitting about the second cylindrical surface, and a segmental cylindrical surface on said filler member complementing the second bearing surface.

3. In a railway coupler, a coupler head, a front stem member carried by the coupler head projecting rearwardly therefrom, a generally cylindrical shaped extension on said stem member in alignment with the longitudinal axis of said stem member, a shoulder on said stem member defining the forward end of said extension, a boss integral with the extension having a larger diameter than the periphery of the extension and arranged intermediate the ends of the extension, a rear stem member having an elongated

gated cavity therein opened lengthwise along the bottom thereof receiving said extension, a filler member closing said cavity and having a bottom surface flush with lower side portions of the rear stem member, cylindrical bearing surfaces within the rear stem member and the filler member journaling the rear end of said extension for rotation about the axis thereof, lugs on said rear stem member and filler member between said boss and said shoulder, and cylindrical surfaces on said lugs forming a bearing fitting about the periphery of said extension forwardly of said boss.

4. In a railway coupler, a coupler head, a front stem member carried by the coupler head projecting rearwardly therefrom, a generally cylindrical shaped extension on said stem member in alignment with the longitudinal axis of said stem member, a shoulder on said stem member defining the forward end of said extension, a boss integral with the extension having a larger diameter than the periphery of the extension and arranged intermediate the ends of the extension, a rear stem member having an elongated cavity therein opened lengthwise along the bottom thereof receiving said extension, a filler member closing said cavity and having an exterior surface flush with outer surface portions of the rear stem member, cylindrical bearing surfaces within the rear stem member and the filler member journaling the rear end of said extension for rotation about the axis thereof, lugs on said rear stem member and filler member between said boss and said shoulder, and the inner surfaces of said lugs being cylindrically shaped forming a bearing fitting about the periphery of said extension between the boss and said shoulder.

5. In a railway coupler, a coupler head, a stem member carried by the coupler head projecting rearwardly therefrom, an extension on said stem member in axial alignment with the longitudinal axis of said stem member, a cylindrical surface adjacent the rear end of said extension, a shoulder on said stem member defining the forward end of said extension arranged in a plane at substantially right angles to said longitudinal axis, an annular boss on said extension of larger diameter than said cylindrical surface and spaced rearwardly from said shoulder and spaced forwardly of said rear end, and a second cylindrical surface on said extension between said boss and said shoulder.

6. In a railway coupler, a coupler head, a stem member carried by the coupler head projecting rearwardly therefrom, an extension on said stem member in axial alignment with the longitudinal axis of said stem member, a cylindrical surface adjacent the rear end of said extension, a shoulder on said stem member defining the forward end of said extension arranged in a plane at substantially right angles to said longitudinal axis, an annular boss on said extension of larger diameter than said cylindrical surface and spaced rearwardly from said shoulder and spaced forwardly of said rear end, a second cylindrical surface on said extension between said boss and said shoulder, an annular shoulder defining the front face of said boss arranged in a plane substantially at right angles to said longitudinal axis, and said annular shoulder defining the rear extremity of said second cylindrical surface.

7. In a railway coupler, a coupler head, a stem member carried by the coupler head projecting rearwardly therefrom, an extension on said stem member in axial alignment with the longitudinal axis of said stem member, a cylindrical surface adjacent the rear end of said extension, a shoulder on said stem member defining the forward end of said extension arranged in a plane at substantially right angles to said longitudinal axis, an annular boss on said

extension of larger diameter than said cylindrical surface and spaced rearwardly from said shoulder and spaced forwardly of said rear end, a second cylindrical surface on said extension between said boss and said shoulder, said stem member having an aperture therein with a mouth at the surface of said shoulder, a ball within said mouth, and a spring within said aperture engaging said ball and the stem member within the aperture.

8. In a railway coupler, a two-part draw bar for the 10 coupler including a front stem member and a rear stem member, said rear stem member having an elongated cavity therein opened along one side and opened at the front end thereof, an end surface on said rear stem member substantially at right angles to the length thereof, an 15 extension carried by the front stem member accommodated within said cavity, shoulders extending lengthwise of said stem member along said cavity, a filler member closing said open side, shoulders on said filler member engaging the first shoulders, means securing the filler member to the rear stem member with said shoulders 20 in engagement, cylindrical bearing surfaces within the rear stem member and filler member journaling the rear end of said extension for rotation about the axis thereof, a boss on an intermediate portion of said extension, lugs 25 on the rear stem member and the filler member between said boss and said end surface, and cylindrical surfaces on said lugs forming a bearing fitting about the periphery of said extension forwardly of said boss.

9. A stem member for a two-part draw bar of a railway 30 coupler comprising, an elongated rear stem member having a cavity therein open at one side and open at the front end thereof, a front end surface on said member substantially at right angles to the length thereof, shoulders extending lengthwise of said member along the boundary of said side opening, a segmental cylindrical surface within said member at the rear end of said cavity with substantially parallel surfaces both tangent to said cylindrical surface extending to said shoulders, lugs at the front end of said stem member having substantially parallel inner confronting edges extending to said shoulders, and a second segmental cylindrical surface connecting and merging with said inner edges on said lugs.

10. A stem member for a two-part draw bar of a railway 35 coupler comprising, an elongated rear stem member having a cavity therein open at one side and open at the front end thereof, a front end surface on said member substantially at right angles to the length thereof, shoulders extending lengthwise of said member along the boundary of said side opening, a segmental cylindrical surface within said member at the rear end of said cavity with substantially parallel surfaces both tangent to said cylindrical surface extending to said shoulders, lugs at the front end of said stem member having substantially parallel inner confronting edges extending to said shoulders, a second segmental cylindrical surface connecting 40 and merging with said inner edges on said lugs, a filler member having portions engaging said shoulders with the filler member closing said side opening, a segmental cylindrical bearing surface on the filler member complementing the segmental cylindrical surface at the rear end of said cavity, and a segmental cylindrical surface on said filler member complementing the segmental cylindrical surface connecting the inner edges on said lugs.
